UNITED STATES PATENT OFFICE.

CLARENCE D. PLATT, OF BRIDGEPORT, CONNECTICUT.

INCLOSED-SWITCH CONSTRUCTION.

1,240,364.

Specification of Letters Patent. Patented Sept. 18, 1917.

Application filed March 3, 1917. Serial No. 152,257.

To all whom it may concern:

Be it known that I, CLARENCE D. PLATT, a citizen of the United States of America, residing at Bridgeport, Conn., have invented a new and useful Inclosed-Switch Construction, of which the following is a specification.

My invention relates particularly to precautions for safety so that fuses may be inserted and replaced by the householder or ordinary user without the possibility of contact with the switch mechanism.

The inclosure may be a box of any suitable character containing any suitable form of switch mechanism and sockets for the usual fuse plugs. An interior insulating cover is provided through which the fuses may be inserted and removed. This insulating cover may be held in place by a screw and provision is made for sealing this screw to the insulating cover so that it is impossible to remove the screw or the cover without breaking the seal.

Figure 1 illustrates a construction embodying the improvements of my invention, part of the cover being broken away and exposing the interior insulating cover and the seal.

Fig. 2, is an enlarged longitudinal sectional view showing the box closed.

Fig. 3, is a detail view of the interior insulating cover.

The switch mechanism may be of any suitable form. As herein shown it has an insulating base 5 which is secured in the body 6 of the box. The movable switch member 7 is adapted to be operated by means of a handle 8 having a shaft 9 pivoted in the box and an offset or eccentric 10. The stationary contacts are not shown but may be of any suitable character.

The insulating base carries suitable terminals for the fuse plugs including screw sockets such as 11 into which a plug such as 12 is adapted to be screwed.

A plate 13 of insulating material is shaped to fit within the body 6 of the box and cover all of the switch mechanism and the usual circuit terminals within the box so that when the plate is in place it is impossible to obtain contact with any of the current carrying parts of the switch. This plate is provided with openings such as 14 for the fuse plugs. The diameter of these openings is such that the flanges of the fuse plugs will overlap the margins of the open-

ings, and thus the fuse plugs when in place will prevent the insulating plate or interior cover from being removed.

The plate 13 is also provided with a central slot 15 for a screw 16. A nut 17 is sealed in the back of the insulating base to receive this screw 16. The head of the screw is larger than the slot 15 so as to hold the plate 13 in place. The head of the screw is provided with a hole 18 and the plate 13 is provided with holes 19 and 20 so that a sealing wire 21 may be passed through the head of the screw 16 and through the insulating cover plate 13 and held by a seal 22. This wire will prevent the rotation of the screw 16 and will thus prevent the removal of the insulating cover plate 13.

The box is preferably provided with an outside metal cover 23 hinged at 24 and having a knob 25. This outside cover may be opened for the purpose of inserting or replacing the fuse plugs. Obviously the switch may be operated by the handle 8 with the cover 23 open or closed, as desired. When it is desired to obtain access to the switch contacts, the seal 22 is broken, the wire 21 removed, the screw 16 unscrewed from its seat, the fuse plugs removed and the insulating cover plate 13 taken out.

I claim:

1. In an inclosed switch construction, a box body, a cover therefor, switch mechanism within the box body and having sockets for fuse plugs, a protective partition within the box body covering the switch mechanism therein and forming a protective covering for said mechanism when the box cover is open, said protective partition having openings therein in line with the fuse sockets of the switch mechanism to thereby enable replacement of fuses without exposure of the switch mechanism, and means for securing the partition in its protective position.

2. In an inclosed switch construction, a box body and a movable cover therefor, an insulating base mounted in the box body, switch parts and fuse sockets on said insulating base, and a protective partition of insulating material secured within the box body in position covering the live parts of the switch mechanism and provided with openings therein in line with the fuse sockets to enable replacement of fuses with-

out exposure of live parts of the switch when the box cover is open.

3. In an inclosed switch construction, a box body, a movable cover therefor, an insulating base mounted in the box body, switch parts and fuse sockets on said insulating base, a protective partition within the box resting on the insulating base, covering the aforesaid switch mechanism and pro-

vided with openings in line with the fuse sockets to enable replacement of fuses without exposure of live parts of the switch mechanism when the box cover is open, means for securing the protective partition to the insulating base and means for sealing said securing means.

CLARENCE D. PLATT.
